UNITED STATES PATENT OFFICE.

CHARLIE THOMAS JONES, OF BLYTHEVILLE, ARKANSAS.

FLYING-MACHINE.

1,090,068.

Specification of Letters Patent. Patented Mar. 10, 1914.

Application filed May 16, 1913. Serial No. 768,112.

To all whom it may concern:

Be it known that I, CHARLIE T. JONES, a citizen of the United States, residing at Blytheville, in the county of Mississippi 5 and State of Arkansas, have invented new and useful Improvements in Flying-Machines, of which the following is a specification.

This invention relates to flying machines 10 of the heavier-than-air class, and particularly to those of the monoplane type, the primary object of the invention being to provide a machine which will develop high speed and is adapted to be readily and 15 easily controlled.

A further object of the invention is to provide a flying machine which will develop maximum climbing and lifting efficiency, and which is adapted to be easily launched 20 and landed without excessive shocks or jars.

A further object of the invention is to provide simple and effective means for maintaining automatic lateral stability, which means will operate to control the lateral 25 tilting of the machine without affecting or being affected by the longitudinal tilting of the machine on its transverse axis in steering the machine upward or downward.

A further object of the invention is to 30 provide a machine which is simple of construction, which embodies a novel construction of balancing planes and automatic controlling mechanism therefor, and which also embodies a novel arrangement of vertical 35 rudders for steering the machine efficiently in either direction laterally, and which also operate as vertical stability surfaces to prevent the machine from skidding and to maintain it against the action of side currents of air in a straight line of flight.

The invention consists of the features of construction, combination and arrangement of parts, hereinafter fully described and claimed, reference being had to the accompanying drawings, in which:

Figure 1 is a front elevation of a flying machine embodying my invention. Fig. 2 is a side elevation of the same. Fig. 3 is a sectional plan view of the same. Fig. 4 50 is a diagrammatic view showing the balancing mechanism.

Referring to the drawings, 1 designates the main frame of the machine, which may be of any suitable construction, and which 55 carries a supporting plane or surface 2. The main frame is provided with a tail ex-

tension 3 and has secured thereto a truss bridge 4 from which the wings of the plane are braced by reinforcing wires 5. Depending from the front of the main frame are 60 standards 6, reinforced therefrom by suitable braces 7 and carrying at their lower ends suitably cushioned ground wheels or rollers 8. These wheels in conjunction with a flexible trail skid 9 support the machine 65 when at rest upon the ground to enable the machine to be launched and landed with a minimum degree of concussion or shocks. The supporting surface or plane is suitably cambered to secure an efficient range of 70 lifting and supporting capacity, with high speed and dirigibility.

The machine is propelled in flight by a front propeller 10 driven from a suitable motor 11.

Upon the main frame is supported the aviator's seat 12, and between said seat and the propeller is arranged a pyramidal-shaped shield 13, adapted to protect the aviator from the force of the wind, as well as 75 from bullets or other missiles when the machine is employed for scouting and the like in military use. The shield operates to deflect the air laterally so that the balancing planes, hereinafter described, will be subjected normally to substantially equal pressures, enabling the machine to be more perfectly controlled and its balance accurately maintained.

The tail frame 3 supports a horizontal 90 rudder 14 carrying a vertical stability fin 15. The rudder is mounted to swing upon a transverse axis 16 to which are attached upwardly and downwardly extending crank arms 17 from which wires or other suitable 95 connections 18 lead to a suitable controlling device 19. This rudder operates to normally maintain the flying attitude of the machine and to hold it straight on its course of travel, and is adjustable by means of the controlling 100 device to steer the machine upward or downward. A coiled spring 20 connects one of the arms 17 with the tail frame to maintain the rudder in its normal position, thus obviating the necessity of the operator maintaining constant hold of the control device.

The machine is adapted to be steered laterally by a pair of vertical rudders 21 disposed beneath the body of the supporting surface on opposite sides of the longitudinal center of the machine, said rudders being hinged or pivoted at their front edges 110

to the main frame so as to be swung inwardly from a normal position parallel with the line of flight. Each rudder is connected at its rear or free edge with the main frame by a coiled spring 21, which serves to return it to normal position after adjustment and operates to maintain it in such position against wind pressure until positively adjusted, thus avoiding the necessity of the operator giving his entire time and attention to the adjusting or steering means. The two vertical rudders are respectively connected by cables 22 with a drum 23, the shaft of which carries a steering wheel 24 arranged adjacent to the aviator's seat. These wires or cables 22 are so arranged as to adapt one to unwind from the drum when the other is wound thereon, so that in adjusting each rudder for a steering action the other rudder will be left unaffected to serve as a stability surface. The rudder 21 at the right hand side of the machine is adjusted inwardly into the path of the wind to steer the machine to the right, while the rudder 21 at the left hand side of the machine is adjusted inwardly to steer the machine to the left. In making these adjusting movements, the operator turns the steering wheel instinctively toward the direction in which it is desired to make the turn. This form of steering mechanism, in addition to its stabilizing action, gives complete control in steering the machine laterally and banking the same in making turns.

Arranged at the opposite sides of the main frame are balancing planes 25 and 26, each mounted adjacent its forward edge upon the main frame to swing vertically upon a horizontal transverse axis 27, and each provided with a rearwardly extending operating arm 28. The said arms 28 are connected at their rear ends by universal sleeve joints 29 to the opposite ends of an intermediate pivoted, transversely and horizontally disposed, vertically swinging lever 30, the arms of which are coupled by pivot joints 31 to the rear ends of a pair of longitudinally extending parallel transmission levers 32. These levers 32 are attached midway of their ends to independent horizontal transverse rods or shafts 33 journaled in a suitable bearing 34 so as to permit said rods to rock in a fore and aft direction. The forward ends of the transmission levers 32 are coupled by universal sleeve joints 35 with the ends of a horizontal transversely extending actuating lever 36, fulcrumed intermediate on the main frame, as at 37. To this lever is secured a depending bracket 38 reinforced therefrom by braces 39, which bracket is bifurcated at its lower end to receive the upper end of a rod 40, which is pivoted thereto to swing in a fore and aft direction, said rod carrying at its lower end a basket or other weighted member or re-

ceptacle 41. The bracket, rod and receptacle act as a unit to form a pendulum lever which when the machine tilts laterally maintains a position perpendicular to the earth's surface, to effect a relative movement between the lever 36 and the body of the machine, and which has its weighted member free to swing in a fore and aft direction when the machine is tilted longitudinally for ascent or descent, so that the balancing mechanism will not interfere with the pivotal motion of the machine on its transverse axis for an up or down steering action. It will thus be understood that when the machine tilts laterally in one direction, say toward the left, the left and right hand arms of the lever 36 will be respectively adjusted upwardly and downwardly and will tilt the levers 32 in opposite directions to throw the balancing plane 26 downward for a lifting action at the depressed side and to throw the balancing plane 25 upward to secure a depressing action at the elevated side, whereby the lateral balancing of the machine will be restored. When the machine tilts in the opposite direction the balancing planes will be reversely tilted to restore the lateral balancing, simple and effective means thus being provided for maintaining automatic lateral stability without interfering with the steering of the machine either longitudinally or laterally.

From the foregoing description, taken in connection with the drawings, the construction and mode of operation and advantages of my improved flying machine will be readily understood, and it will be seen that advantages of importance are attained which enable a machine to be controlled with ease and high speed to be obtained. Inasmuch as the balancing mechanism is entirely automatic, while the steering devices are of a type which do not require constant attention, it will be seen that the aviator will be given sufficient time to make observations, drop projectiles, and to perform other services, rendering the machine particularly available for observation and military work. The construction and arrangement of the balancing planes, vertical rudders and shield, not only provide for the protection of the aviator from air pressure and missiles, but for an equal distribution of the air toward the opposite sides of the machine to render the operation of the balancing planes and rudders complementary in character, making the machine much more stable and easier to steer than would otherwise be the case.

Having thus described the invention, what I claim as new is:

1. In a flying machine, a gliding structure, an aviator's seat thereon, vertical rudders positioned at the right and left hand sides of the gliding structure, means for ad-

justing the same, a motor driven shaft carrying a propeller, balancing planes mounted at the right and left hand sides of the machine for adjustment in opposite directions in unison, and a shield disposed between the propeller and aviator's seat and having inclined guiding surfaces for directing the air pressure equally toward the supporting surface, rudders and balancing planes.

10 2. In a flying machine, a gliding structure, balancing planes mounted to tilt vertically at the right and left hand sides of said structure, front and rear vertically swinging levers, the latter being operatively connected on opposite sides of its pivot with said balancing planes, a connection between the levers for tilting the rear lever oppositely to the front lever when the latter is actuated, and a pendulum controlling said front lever.

15 3. In a flying machine, a gliding structure, pivoted vertically movable balancing planes at the opposite sides of the gliding structure, a vertically swinging lever op-

eratively connected with said planes on opposite sides of its pivot, a correspondingly mounted operating lever, rocking elements connecting the similar ends of said levers and pivoted at points between the same, 30 and a pendulum controlling the operating lever.

4. In a flying machine, a gliding structure, pivoted vertically swinging balancing planes at the opposite sides thereof, front 35 and rear intermediately pivoted vertically swinging levers, the arms of the rear lever being pivotally connected with the respective balancing planes, rock shafts disposed between the two levers, transmission levers 40 intermediately connected with the rock shafts and pivotally coupled at their ends to said front and rear shafts, and a pendulum controlling the front shaft.

In testimony whereof I affix my signature 45
in presence of two witnesses.

CHARLIE THOMAS JONES.
